UNITED STATES PATENT OFFICE.

HARRY F. WHITE, OF FRESNO, CALIFORNIA.

SCRIP-MEASURING DEVICE.

1,407,106.

Specification of Letters Patent. Patented Feb. 21, 1922.

Application filed January 26, 1921. Serial No. 440,061.

To all whom it may concern:

Be it known that I, HARRY F. WHITE, a citizen of the United States, residing at Fresno, in the county of Fresno and State of California, have invented certain new and useful Improvements in Scrip-Measuring Devices, of which the following is a specification.

In the sale of some commodities such for example as gasoline and oils or in negotiating for passenger traffic, it is the custom of some companies to issue books of scrip comprising for example leaves or a strip having a series of divisions each designated to indicate a unit of value which may have its equivalent in money, miles, gallons or other liquid units of measure, etc., and from which book the company agent will remove a greater or less number of units corresponding to the quantity of the commodity purchased or other payment to be made in return for service, when the book is presented by the purchaser. In the use of such books however considerable time is consumed and errors are likely to be caused in counting off or calculating the number of units to be removed. Particularly is this true when the scrip units are designated to indicate successive totals throughout the series for in such case it is necessary frequently to subtract or add odd amounts in order to determine the location of the unit at which the scrip is to be torn or otherwise detached. Therefore it is the primary object of the present invention to provide means for employment in connection with scrip of the character mentioned, for the purpose of measuring off the required number of units and thus immediately locating the point at which the scrip is to be torn or otherwise removed, and without the necessity of arithmetical calculation.

Another object of the invention is to provide a device which may be employed either as a separate and independent device, and used either at the time the scrip is presented by the purchaser, in determining the number of units of scrip to be removed from the book, or by an employee in calculating the number of units embraced in blocks of units of scrip turned in by the company agents.

In the accompanying drawings:

Figure 1 is a perspective view of a scrip book and the device embodying the invention arranged therein;

Figure 2 is a similar view illustrating the

manner of using the device in connection with the scrip embraced in the book.

The device embodying the invention is applicable to scrip in various forms but is illustrated in the drawing as employed in connection with scrip in the form of a folded strip arranged between covers in book form, and in the said drawing the numeral 1 indicates one cover leaf and the numeral 2 the other cover leaf, the leaves being connected in any ordinary manner. The scrip which is indicated in general by the numeral 3 comprises a strip which is secured at one end to the inner side of one of the cover leaves as for example the leaf 2 and which is folded back and forth upon itself at intervals so as to reduce it, in its folded condition, to dimensions to permit of its being housed between the leaves 1 and 2. The scrip is as stated above in the form of a strip and upon one face of this strip are printed for example transverse lines 4 which serve to divide the strip into a number of units 5 each of which in the illustrated embodiment of the invention is printed with numerals 6 which, when any portion of the strip is torn off along any one of the lines 4, will indicate or designate the total amount of scrip which has been removed from the book. Thus in the present instance scrip has been removed from the book to the total value of \$6.75 so that the designation 6 of the terminal unit of the remaining scrip reads \$6.80. The values which designate the units, however, might be in terms of, for example, liquid measure, and the units might be consecutively numbered, instead of being individually numbered consecutively or otherwise, or merely bear data indicating their individual value. Therefore, the drawings are merely to indicate an example of scrip in connection with which the device of the invention may be employed. If, for example, the scrip illustrated in the drawings should be that issued by a company dealing gasoline and oils and if, in the illustrated condition of the scrip the purchaser of the book should desire to purchase gasoline to the value of 90¢ it would, under the practice usually followed, be necessary to calculate by a process of addition the designated value of the particular unit or division 5 at the dividing line of which the scrip should be severed in order to remove the block of units equivalent to 90¢. Or, by another method, considering the value of each unit or division to be 5¢,

eighteen of the units might be counted off and this block of units removed. As previously stated, however, this method of calculation is time-consuming and subject to 5 error.

The device embodying the present invention is indicated in general by the numeral 7 and comprises a strip 8 of any suitable material and preferably flexible. For example, 10 the strip may be made from tracing linen in which event it would possess the advantage of being practically transparent. One end of the strip is secured, as at 9, in any suitable manner within the book as for example to 15 the inner face of the cover leaf 1 and the remaining length of the strip is folded back and forth upon itself at suitable intervals so that as in the case of the scrip it may occupy a position wholly within the bounds of 20 the cover leaves when the book is closed. For a portion of its length indicated in general by the numeral 10, the strip 8 is marked off as for example by lines 11 into divisions 12 corresponding, in the spacing of their 25 boundary lines 11, to the divisions 5 of the scrip, and the said lines 11 are designated individually by numerals, as at 13, arranged in sequence throughout the series and, in the illustrated example, from "0 to 100", 30 each designation being greater by five than the preceding designation throughout the series. Thus, the portion 10 of the strip 8 is of a length equal to the length of a block of the units 5 equivalent to \$1.00, or in other 35 words equivalent to the length of a block of twenty of said units 5. At a point spaced from the line 11 which is designated by "0" on the measuring strip 8, equivalent to the length of the said portion 10 of the strip, 40 another line 14 is indicated upon the said strip and may be designated for example by numerals indicating a value of \$1.00, as indicated by the numeral 15, and at correspondingly spaced intervals other lines are 45 indicated upon the strip and are given numerical value designations. Thus the strip 8 may be said to have a portion of its length divided into units of measurement and an-

other portion into multiples of such units.

In the use of the device and assuming 50 that the same is to be employed in the specific example given above, the line 11 of the measuring strip which is indicated at 13, by 90, is brought into registration with the extremity of the scrip 3, and the portion 55 10 of the said measuring strip flat along the scrip to bring that one of the lines 11 which is designated by "0" into measuring relation to the face of the scrip whereupon it will be found that this line registers with 60 the boundary line of the unit of division 5 which is designated by \$7.70. In this manner the device indicates the proper division line 4 along which the scrip must be severed in order to remove therefrom a block of the 65 units or divisions 5 equivalent in value to 90¢. If the purchase to be made should amount to, for example \$1.90, then the device would be employed as above described except that the full length of the measuring 70 strip would be laid along the length of the scrip and line 14 bearing the dollar designation 15 had been brought into registration with one of the lines 4 of the scrip.

Having thus described the invention, what 75 is claimed as new is:

The combination with scrip having a series of designated divisions which are to be removed in blocks of selected numbers, of means for application thereto to measure off any selected number of said divisions, said means consisting of a strip having one end portion of its length divided into units equal in length to the divisions of the scrip and the remaining portion of its length divided into multiples of such units, the units being numbered to represent total values in ascending sequence with the unit of greatest value at the extremity of that end portion of the strip containing the unit divisions and 85 the divisions representing multiples of the units being numbered in sequence toward the opposite end of the strip from the unit of lowest value.

In testimony whereof I affix my signature. 90
HARRY F. WHITE. [L.S.]
